US00D821807S

(12) **United States Design Patent** (10) **Patent No.:** **US D821,807 S**
(45) **Date of Patent:** **** Jul. 3, 2018**

(54) **LID FOR HOUSEHOLD CONTAINER OR THE LIKE**

(71) Applicant: **DKB Household UK Limited, Hampshire (GB)**

(72) Inventors: **Jason Yap, Melbourne (AU); Oliver Breit, Discovery Bay (HK)**

(73) Assignee: **DKB Household UK Limited (GB)**

(**) Term: **15 Years**

(21) Appl. No.: **29/558,135**

(22) Filed: **Mar. 15, 2016**

(30) **Foreign Application Priority Data**

Sep. 18, 2015 (EM) 002775528-0001

(51) LOC (11) Cl. **07-01**

(57) **CLAIM**

The ornamental design for a lid for household container or the like, as shown and described.

DESCRIPTION

FIG. 1 is an isometric view of a lid for household container or the like in accordance with the present design;

FIG. 2 is a top plan view thereof;

FIG. 3 is a front elevation view thereof;

FIG. 4 is a rear elevation view thereof;

FIG. 5 is a right side elevation view thereof; and,

FIG. 6 is a left side elevation view thereof.

The dash-dash broken lines illustrate features of the lid for household container or the like and environmental structure that form no part of the claimed design. The dash-dot-dash broken lines illustrate the boundaries of the claim and form no part thereof.

1 Claim, 6 Drawing Sheets
